UNITED STATES PATENT OFFICE.

AUGUSTUS W. SHANK, OF DETROIT, MICHIGAN, ASSIGNOR TO EDWARD A HALL AND WILLIAM C. HOLLAR, OF DETROIT, MICHIGAN.

STREET-CAR FENDER.

SPECIFICATION forming part of Letters Patent No. 699,769, dated May 13, 1902.

Application filed May 13, 1901. Serial No. 59,936. (No model.)

To all whom it may concern:

Be it known that I, AUGUSTUS W. SHANK, a citizen of the United States, residing at Detroit, in the county of Wayne, State of Michigan, have invented certain new and useful Improvements in Street-Car Fenders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to street-car fenders; and it consists in the construction and arrangement of parts hereinafter fully set forth, and pointed out particularly in the claims.

The object of the invention is to provide 20 simple and efficient means for attaching the fender to the front of the car-frame in such manner as to suspend said fender so as to allow a free vertical movement of the forward end thereof, the arrangement being such as 25 to allow the forward end of the fender to be dropped to the rails of the track when desired to prevent a person or object from passing under the fender in case of accident. A further arrangement provides for raising the 30 forward end of the fender after being depressed and maintaining it in its normal or raised position.

The above object is attained by the mechanism illustrated in the accompanying drawings, in which—

Figure 1 is an elevation of a street-car to which my improved fender is applied, the upper portion of the car being broken away. Fig. 2 is a plan view of the forward end of 40 the car-frame, showing my improved fender mounted thereon. Fig. 3 is a side elevation of Fig. 2. Fig. 4 is a front elevation of Fig. 3. Fig. 5 is a detail in perspective showing the parts of the fender and one of the operative chains attached thereto. Fig. 6 is an enlarged detail, partly in section, showing the dog or detent adapted to engage the ratchet on the upper end of the shaft, carrying at its lower end a drum upon which the chains are 45 wound that operate the fender.

Referring to the characters of reference, 1

designates the frame of the car, which may be of any suitable construction and to the forward end of which the fender is pivotally hung. The fender 2 may be of any suitable 55 construction, and comprises a horizontal forwardly-projecting portion 3 and a vertical portion 4, crossed by suitable slats or bars. Extending rearwardly from the upper portion of the fender, on each side thereof, is a side 60 bar 5. The rear ends of said side bars are pivoted at 6 in a suitable bracket 7, adapted to be secured to the under face of the car-frame, whereby the fender becomes hinged or pivoted, so that the forward end thereof 65 may swing in the arc of a circle concentric with the point of pivot 6.

Attached to each of the side bars 5 is a chain 8, adapted to pass over a roller 9, hung below the under face of the car-frame, and 70 thence horizontally to a drum 10, secured to the lower end of a vertical shaft 11, journaled in the frame of the car and carrying at its upper end, which projects through said frame, a ratchet-wheel 12. Pivoted to a plate 13, 75 mounted upon the upper face of the platform of the car, is a detent or dog 14, having a laterally-extending hook 15, which engages the notches of the ratchet-wheel 11 and holds said wheel from rotation. The upper end of the 80 shaft 11 is squared for the application of a crank or wrench, as shown by dotted lines in Fig. 6, whereby said shaft may be rotated to revolve the drum 10 and wind the chains 8 thereon to raise the fender and maintain it 85 in its normal position, as shown in Fig. 1. The detent 14 is disengaged from the ratchet as the fender is being raised and reengaged therewith when the fender has been elevated to maintain it in position.

It will be observed that by means of the arrangement shown and described the entire weight of the fender is forward of the point of pivot 6, so that the forward end of said fender will readily fall when the supporting- 95 chains 8 are released.

With the parts in their normal position the forward end of the fender may be dropped to the rails of the track by depressing the free end of the detent 14, which will carry the 100 hook of said detent from engagement with the ratchet, thereby allowing the chains to

unwind from the drum 10 and permitting the forward end of the fender to fall to the track, in which position it is held by its own weight until again raised, obviating the possibility 5 of any object passing thereunder when in its depressed position. To raise the fender after being depressed, the drum 10 is rotated by means of a crank or wrench to wind the chains 8 thereon, as before described.

10. Embracing the side bars of the fender are the staples 16, which serve as guides to steady the fender in its movement. When the fender is down, as shown in Figs. 3 and 4, there will be sufficient slack in the chains 8 to prevent 15 the front of the fender being raised from the track by any tilting motion of the car.

This improved safety-fender may be readily attached to any car for use with but comparatively little expense, and by means of 20 the arrangement herein shown said fender may be dropped so quickly in case of an emergency as to prevent a person or object from passing under the fender to be encountered by the wheels of the car. In its normal 25 use the fender is so flexibly hung that it will readily give and yield, so as to ride over any obstruction on the track without damage to the fender.

Upon the plate 13 is a shoulder 17, adapted 30 to partially embrace the engaging end of the detent 14, so as to prevent the force exerted by the weight of the fender upon the ratchet-wheel crowding said detent from engagement with said wheel and allowing the fender to 35 accidentally drop.

Under the free end of the detent 14 is a coiled spring 18, adapted to raise said end of the detent after being depressed and more surely retain the engaging end thereof in contact 40 with the ratchet-wheel.

Having thus fully set forth my invention, what I claim as new, and desire to secure by Letters Patent, is—

1. In a car-fender, the combination with the 45 car-frame, of a fender-frame hinged at its rear end to the frame of the car and adapted at its forward end to swing downward by gravity into contact with the rails of the track in advance of the car-frame, pulleys journaled on 50 the car-frame on either side thereof, a drum journaled centrally to the car-frame, chains attached directly to the opposite sides of the fender-frame passing upwardly over said pul-

leys and horizontally to and around said drum whereby the fender-frame becomes suspended 55 above the track-rails to move freely in the arc of a vertical circle, means for rotating said drum to draw upon said chains and raise the fender, a ratchet-wheel upon the shaft of said drum having peripheral teeth, a plate upon 60 the platform adjacent thereto, a curved detent pivoted at the center to said plate and adapted to engage the teeth upon the periphery of the ratchet, the engaging end of said detent being adapted to move vertically, a 65 curved shoulder on said plate coinciding with and embracing the curved end of said detent when said detent is in engagement with the ratchet, a tread upon the free end of the detent to enable it to be raised at its curved end 70 and disengaged from said ratchet-wheel to release the drum and allow the chains to run slack when the fender is down and avoid imparting to the fender the tilting movement of the car-frame. 75

2. In a street-car fender, the combination with the frame of the car, of the fender pivoted thereto so as to allow the forward end thereof to swing vertically, the upper side bars of the fender-frame lying close to the 80 bottom of the car above the plane of the horizontal forward portion which is connected to the upper side bars by a vertical section and stands parallel with the track, chains attached directly to the opposite upper side bars of the 85 fender-frame forward of said point of pivot and running freely to loosely suspend the forward end of the fender above the track and allow of a tilting and swaying movement thereof, said chains passing vertically over suitable 90 rollers and horizontally to a rotary drum, means for rotating said drum to wind the chains thereon and raise the fender, means for locking the drum against rotation to maintain the fender in its raised position and 95 means for unlocking said drum to permit the chains to unwind freely therefrom and the forward end of the fender to drop to the track by gravity.

In testimony whereof I sign this specification in the presence of two witnesses.

AUGUSTUS W. SHANK.
